PAPER ROLL HOLDER

Herbert Harvey, Los Angeles, Calif., assignor to
Leo M. Harvey, Los Angeles, Calif.

Application January 8, 1937, Serial No. 119,611

10 Claims. (Cl. 242—55.2)

This invention relates to a holder or dispenser for paper, etc., and relates more particularly to a rack or holder for a paper roll or paper towel roll or the like. A general object of this invention is to provide a simple, practical, inexpensive paper roll holder of the character mentioned that is particularly convenient to use or operate.

Various devices have been introduced for holding rolls of paper and rolls of paper toweling. In most of these prior devices the parts or trunnions supporting the ends of the paper roll have been urged against the roll to form brakes or drags to resist rotation of the roll when it is desired to part or tear free the unreeled paper or towel. Such prior devices have not proved altogether satisfactory because in most instances the user is obliged to place his hand on the paper roll to hold it against rotation when he wishes to tear free a length of paper or a towel. This is very undesirable, particularly where the user's hands are wet or soiled.

Another object of this invention is to provide a holder for a roll of paper or a roll of paper toweling or the like in which it is unnecessary to place the hands on the roll to hold the same against rotation when it is desired to part or tear free a length of unreeled paper or toweling.

Another object of this invention is to provide a paper roll holder of the character mentioned in which the roll is automatically locked against rotation and the paper toweling is held against further unreeeling movement when the user draws the reeled-off paper strip outwardly or maintains a forward pull on the strip.

Another object of this invention is to provide a paper roll holder of the character mentioned in which the means for locking or holding the roll and the paper against movement to facilitate the tearing free of an unreeled length of paper does not require manual manipulating or setting and is entirely automatic in operation.

Another object of this invention is to provide a paper roll holder of the character mentioned in which the means for holding the roll and the unreeled paper against movement to facilitate the tearing free of the paper does not interfere with or retard the free unreeeling of the paper or the free turning of the roll when the user is unreeeling the paper from the roll.

A further object of this invention is to provide a paper roll holder of the character mentioned that is simple and inexpensive and that is slight and compact.

The various objects and features of my invention will be fully understood from the following

detailed description of a typical preferred form and application of the invention, throughout which description reference is made to the accompanying drawing, in which:

Fig. 1 is a front elevation of the holder provided by this invention showing a paper roll in position in the holder. Fig. 2 is a substantially central vertical detailed sectional view of the holder showing the roll in elevation. Fig. 3 is a reduced view similar to Fig. 1 illustrating the operation of the means for locking the paper roll against movement, and Fig. 4 is an enlarged fragmentary horizontal detailed sectional view of one end portion of the holder.

The present invention is adapted to be embodied in devices for holding rolls of material of various character, for example the invention may be embodied in form for holding toilet paper, paper towel rolls, rolls of wrapping paper, etc.

In the following detailed disclosure I will describe a typical form of the invention adapted to hold a roll of paper toweling of the character that is widely used in kitchens of residences, in wash rooms, etc. It is to be understood that this invention is not to be construed as limited to the particular form and application of the invention about to be described. The typical roll R of paper or paper toweling illustrated may be considered as a continuous elongate sheet or strip S wound on a tubular spool 10. The strip S is provided with longitudinally spaced transverse lines of perforations 11 to facilitate the separation or parting of its individual towels.

The holder of the present invention includes, generally, a suitable bracket or base 12, spaced projecting arms 13 on the base 12 for rotatably supporting the roll R and means 14 operable to lock the roll R against rotation when it is desired to tear free or part an unreeled towel or portion of the paper strip S.

The bracket or base 12 of the holder may be varied to adapt the device for different installations. In the particular case illustrated, the base 12 is a substantially rectangular member adapted for arrangement on a vertical support such as a wall. The base 12 may have an inwardly or rearwardly turned flange 15 extending along its margins or edges. Suitable means are provided for facilitating the attachment of the base 12 to a support. In the structure illustrated, the base 12 has spaced depressed portions 16 provided with slots or openings 17 for receiving securing members such as screws or the like for attaching the base to the support.

The arms 13 project outwardly or forwardly

from the base 12 to support the roll R. In the construction illustrated the arms 13 project outwardly through vertical slots 18 in the end portions of the base 12. The arms 13 pass through the slots 18 with substantial clearance so that they may have limited tilting or rocking movement. A laterally turned flange 20 is provided on the inner end of each arm 13 and is adapted to engage against the inner side of the base 12 to prevent outward loss or displacement of the arms 13. The outer portions of the arms 13 are pressed or shaped to have projecting trunnions or projections 21 adapted to enter the ends of the spool 10 to rotatably support the roll R. Raised bosses 22 may be provided at the bases of the projections 21 to hold the ends of the roll R spaced from the arms 13. Flanges 23 are provided on the outer sides of the arms 13 and extend along the longitudinal edges of the arms. The inner ends 24 of the flanges 23 are pitched or inclined relative to the arms 13 and are adapted to engage the outer face of the base 12 to limit the outward pivotal movement of the arms 13. The above described flanges 20 may cooperate with the inner side of the base 12 to limit the outward pivotal movement of the arms 13 or to assist in this function.

Means are provided to normally hold the arms 13 against movement in positions where their projections 21 extend into the ends of the roll spool 10 to rotatably support the roll R. Straps 25 are welded or otherwise fixed to the flanges 20 of the arms 13 and are riveted or otherwise secured to the base 12. The straps 25 are sufficiently rigid to normally hold the arms 13 in their normal positions where their projections 21 extend into the spool 10 to support the roll R for free rotation. The straps 25 are adapted to yield to allow the arms 13 to be pivoted outwardly or away from one another to facilitate the insertion of the roll R and the removal of the spool 10 when the roll is exhausted.

The means 14 is an important feature of the invention. The means 14 is provided to lock or hold the roll R against rotation and to hold the unreeled portion of the paper strip S against movement when the user wishes to tear free or part an unreeled portion of towel from the strip. It is a feature of the invention that the means 14 does not interfere with the normal free rotation of the roll R when the paper or towel strip S is being unreeled. The means 14 is characterized by its extreme simplicity and comprises only two parts; namely, a rod 27 and a roller 28 on the rod.

The rod 27 of the means 14 is a substantially U-shaped integral member. The rod 27 extends across the outer side of the base 12 and has laterally projecting arms 29 at its opposite ends which are disposed adjacent the ends of the base 12. The arms 29 are of substantial length and are provided at their outer or upper ends with in-turned fingers 30. The fingers 30 are received in openings 31 in the flanged ends of the base 12 to support the rod 27 for oscillation or swinging movement. The openings 31 receiving the fingers 30 of the rod 27 are preferably located adjacent the top of the base 12. The rod 27 supported by the fingers 30 as just described, is adapted to hang free with its transverse or horizontal main portion adjacent the lower edge of the base 12. The roll R is arranged between the arms 13 so that the paper strip S hangs from its rear peripheral surface as illustrated throughout the drawing. The portion of the strip S hanging from the roll R is trained behind the rod 27 as best illustrated in

The roller 28 is carried on the rod 27 to be engaged by the strip S and to cooperate with the roll R to lock the roll against rotation and to prevent further unreeling of the strip S when the user pulls outwardly or forwardly on the strip S of paper or toweling. The roller 28 is preferably rotatable on the rod 27 and may be a simple integral member of rubber, hard rubber composition, wood or the like. In practice the roll 28 may be relatively short as shown in the drawing. In the preferred construction roller 28 is equally spaced between the arms 29 of the rod to be engaged by the central portion of the strip S and to cooperate with the central portion of the roll R. The roller 28 is held against excessive longitudinal movement on the rod 27. In the simple construction illustrated, the intermediate portion of the rod 27 is offset or eccentric and the roller 28 is rotatable on the eccentric portion of the rod 27 to be held against longitudinal movement by the bent parts or shoulders 32 occurring at the ends of the eccentric portion of rod.

It will be observed that the strip S of the toweling or paper depending from the roller R is trained behind the rod 27 and the roller 28 so that the rod 25 and roller are swung forwardly when the strip S is pulled outwardly or forwardly. In accordance with the invention the lower edges of the arms 13 are cut away or provided with notches 33 to receive the rod 27 when the roll R is reduced in diameter and an outward pull is put on the strip S as described above. The notches 33 are such that they allow the roller 28 to bear forwardly against the roll R when the roll is almost exhausted.

In operation or use the paper roll or towel roll 35 R is inserted between the arms 13 so that the trunnion projections 21 fit into the ends of its spool 10. The roll R is arranged so that the strip S leaves the rear side of its periphery which faces the support or base 12. The portion of the strip 40 S leaving the roll R is trained between the base 12 and the roller 28. It is to be understood that the paper or towel roll R is supported by the trunnion projections 21 for free rotation.

To unreel a length of the strip S or a towel of 45 the strip S the user merely pulls downwardly on the strip to unreel a portion of the same from the roll R. During the unreeling of the strip S the roller 28 may engage against the strip S but does not engage against the roll R and, therefore, does 50 not interfere with free turning of the roll. When a sufficient portion of the strip S has been unreeled the user merely pulls outwardly on the strip S in the direction indicated by the arrow A in Fig. 3. When the strip S is pulled outwardly 55 in the direction indicated of the arrow A the strip swings the roller 28 forwardly and upwardly against the roll R. In this regard it is to be noted that the roll 28 is supported by the rod 27 for free swinging movement. The user may apply a substantial forward or outward strain on the strip S to forcibly press the roller 28 against the rear peripheral surface of the roll R which faces or opposes the base 12. The force thus applied to the strip S, of course, tends to move the strip 60 S in the direction indicated by the arrow A and tends to turn the roll R in the direction indicated by the arrow B. The outward movement and pull on the strip S in the direction indicated by the arrow A tends to turn the roller 28 in the direction indicated by the arrow C. Thus it is seen that the roll R and the roller 28 tend to turn in the same direction. The roller 28 being forcibly held against the rear surface of the roll R and tending to turn in the same direction as the 75

roll R operates to stop turning of the roll and to lock the roll against further movement. The co-operating roll R and roller 28 operate to hold one another against rotation when a sufficient outward tension is applied to the strip S in the direction indicated by the arrow A. The roll 28 being stationary or held against movement by the roll R resists or prevents unreeling movement or outward movement of the strip S, the strip being trained across the rear peripheral portion of the roller 28. Thus the roll movement by simply applying a forward or outward pull on the strip S in the general direction indicated by the arrow A. When the roll R becomes locked against turning in this manner the user may easily part or tear free the unreeled portion of the strip S or the outermost towel of the towel strip. When the strip S is provided with the series of perforations 11 it readily parts at the outermost row of perforations 11 so that the user obtains a towel from the strip. Immediately following the tearing free or parting of the towel from the strip S, the portion of the strip hanging from the roll R is usually allowed to fall and hang free, whereupon the rod 27 carrying the roller 28 automatically returns by gravity to a position such as is illustrated in Fig. 2. Thus the device is automatically reconditioned for a further operation.

30 The present invention provides a simple inexpensive paper roll holder embodying the means 14 for automatically locking the roll R against turning when it is desired to part or tear free an unreeled portion of the strip S or a towel of the strip S. The means 14 is entirely automatic in its operation and does not interfere with the free unreeling of the strip S from the roll R so long as the strip is pulled downwardly or in a general downward direction. It is to be noted that the roll R is normally free for rotation and that there is nothing to interfere with the free easy unreeling of the strip S from the roll. The means 14 for automatically locking the roll against turning is extremely simple and does not complicate the general holder construction.

45 Having described only a typical preferred form and application of my invention, I do not wish to be limited or restricted to the specific details herein set forth, but wish to reserve to myself any 50 variations or modifications that may appear to those skilled in the art or fall within the scope of the following claims.

Having described my invention, I claim:

1. A holder for a roll of sheet material comprising, a body, means on the body for supporting the roll for rotation about a fixed axis and to have the strip of material unreel from its back side, and a roller swingably supported on the body between the roll and said strip to be swung 60 against the roll by said strip to stop rotation of the roll when the said strip is pulled outwardly.

2. A holder for a roll of sheet material comprising, a body, means on the body for rotatably supporting the roll to have the strip of material unreel from its peripheral surface opposing the body, and means for holding the roll against rotation to facilitate the parting of said strip from the roll, said means including a part between the roll and the portion of the said strip leaving the 70 roll, means supporting the part on the body for oscillation toward and away from the roll, and a roller on said part engageable by the strip and movable against the roll by the strip when the latter is pulled outwardly.

75 3. A holder for a roll of sheet material com-

prising, a body, means on the body for rotatably supporting the roll to have the strip of material unreel from its inner side, and means for holding the roll against rotation to facilitate the parting of said strip from the roll, said means including a part between the roll and the portion of the said strip leaving the roll, means swingably supporting the part on the body for movement toward the roll, and a roller rotatable on said part engageable by the strip and movable against the roll by the strip when the latter is pulled outwardly.

4. A holder for a roll of sheet material comprising, a body, means on the body for rotatably supporting the roll to have the strip of material unreel from its inner side, and means for automatically holding the roll against rotation when an outward pulling force is applied to the unreeled portion of the strip, said means including a rod extending substantially parallel to the longitudinal axis of the roll and positioned between the roll and the portion of the strip leaving the roll, means connecting the rod with the body for swinging movement toward the roll, and a brake member carried by the rod to be normally clear of the roll and engaged by the strip to be moved against the roll when the strip is pulled outwardly.

5. A holder for a roll of sheet material comprising, a body, means on the body for rotatably supporting the roll to have the strip of material unreel from its inner side, and means for automatically holding the roll against rotation when an outward pulling force is applied to the unreel portion of the strip, said means including a rod extending substantially parallel to the longitudinal axis of the roll and positioned between the roll and the portion of the strip leaving the roll, arms on the rod pivotally carried by the body to support the rod for swinging movement, and a brake member on the rod engaged by the strip to be moved outwardly against the roll when the strip is pulled outwardly and movable out of contact with the roll when the outward pull on the strip is relaxed.

6. A device of the character described for holding a roll of sheet material comprising, a base adapted to be arranged on a support, spaced arms projecting outwardly from the base, parts on the arms for entering the ends of the roll to rotatably support the roll, the roll being arranged so that the strip is unreel from its inner side, a rod extending substantially parallel to the longitudinal axis of the roll between the roll and the portion of the strip extending from the roll, arms on the ends of the rod, fingers on the arms of the rod pivotable in openings in the base to swingably support the rod, and a roller rotatable on the rod and engaged by the strip and moved against the roll to stop the same when the strip is pulled outwardly.

7. A holder for a roll of paper including, means for supporting the roll for rotation about a fixed axis and to have the paper strip unreel from its inner side, a member between the roll and the strip, and means supporting the member to swing out of contact with the roll and to be swung against the roll by the strip when the strip is drawn outwardly.

8. A holder for a roll of paper including, means for supporting the roll for rotation about a fixed axis and to have the paper strip unreel from its inner side, a member between the roll and the paper strip extending therefrom, and means shiftably supporting the member to normally re-

main clear of the roll and to be engaged by the strip whereby an outward pull on said strip causes the strip to swing the member against the roll to hold the same against rotation.

- 5 9. A holder for a roll of sheet material comprising, a body, means on the body for rotatably supporting the roll to have the strip of material unreel from its back side, and means for holding the roll against rotation to facilitate the parting of said strip from the roll, said means including a part directly engaged by the portion of the said strip leaving the roll, and means swingably supporting said part to be swung forwardly against the roll to hold the roll against rotation when
- 10 the strip is pulled forwardly and to swing out of
- 15

contact with the roll when said forward pull on the strip is relaxed.

10. A holder for a roll of sheet material comprising, a body, means on the body for rotatably supporting the roll to have the strip of material unreel from its inner side, and means cooperating with said strip to permit free downward movement of the strip and operable to prevent outward movement of the strip, the last mentioned means including a part supported on the body to normally be free of the roll and engaged by said strip and movable outwardly thereby to have direct braking engagement with the inner side of the roll.

HERBERT HARVEY. 15
